UNITED STATES PATENT OFFICE.

F. BENEDICT HERZOG, OF NEW YORK, N. Y.

CIRCUIT-CHANGER FOR LATENT-SIGNAL TRANSMISSION.

SPECIFICATION forming part of Letters Patent No. 314,294, dated March 24, 1885.

Application filed February 10, 1885. (No model.)

To all whom it may concern:

Be it known that I, F. BENEDICT HERZOG, a citizen of the United States, residing at New York, in the county and State of New York, have invented a new and useful Improvement 5 in Circuit-Changers for Latent-Signal Transmission, of which the following is a specification.

In Letters Patent No. 289,834, issued to me December 11, 1883, I have described an automatic signaling apparatus applicable to many different uses, (such as telephone-exchange service, district-telegraph and private circuits, hotel-annunciators, &c.,) the main feature of 15 which is that the apparatus may be properly set by a person desiring to signal to a distant point, and is so constructed that the desired signal is not transmitted at the moment of setting the instrument, (as is the case in instruments of the kind known as "transmitters;") but the apparatus retains the signal as set until it is released directly or indirectly from a distant point by the person who is to receive the signal at the moment he is ready for 25 it, when the signal is automatically transmitted to such receiver. This instrument is capable of being set so as to transmit one and two alterable signals or combinations of signals, and enables the sender to convey to the receiver any desired information within the limit 30 of two sets of signals. In this and other pending and future applications I call such an instrument a "latent-signal transmitter."

In other applications (Serial No. 144,194 and Serial No. 149,240) I have described apparatus of the above character, but which admit of sending any number of sets or groups of signals instead of only two.

In other applications I have shown that it is often desirable that the one who sets the latent-signal transmitter should be able to signal to the office that it is so set and is ready to be released. I have also shown that it is very desirable to be able, first, to set the instrument to transmit the desired signal, and then, after it is set, to indicate this fact to the receiving-station; and have also shown that if this is done it is necessary to provide "safety" means, whereby the act of calling the atten-

tion of the receiving-office shall not at the 5 same time release the latent-signal transmitter. I have shown several ways in which this can be done under various conditions—as, for instance, between two stations and between a central station and a number of sub-stations— 55 all of which ways, however, have been modifications of my general invention, and have, moreover, shown a constant source of current in circuit.

The object of this invention is to show how 60 the receiving-station can be called after the latent-signal transmitter is set without, by the act of calling, releasing its retaining mechanism in the general case where there is normally no current in line, and particularly 65 where the ordinary magneto-generator is used, as is customary in telephone-stations.

In the accompanying drawings I show the necessary mechanism for this purpose as applied particularly to a form of my latent-signal transmitter, which I show and make the subject of another application filed December 1, 1884, Serial No. 149,240, to which application reference is hereby made for such of the details of the mechanism as are not necessary 75 to the proper working of this present application.

In the drawings, R represents, generally, a suitable back board; A, an extension-bell in common use in telephone-exchange systems; 80 C, my apparatus as applied to a telephone (where it is used for the purpose of enabling a subscriber to set his instrument so as to indicate the number of any subscriber in the system with whom he wishes to be connected, 85 so that he can thereupon go about his ordinary business without paying further attention to the telephone or speaking with the operator until the subscriber whom he has called is at the telephone, or until he has received 90 from the central office a signal indicating either that the called subscriber does not respond, or that the line is "busy.")

D represents a magneto to the front of 95 which my apparatus C is attached, or with which it is incorporated.

B represents the crank of the magneto-machine; P, a disk rigidly fixed to the shaft of

the crank B; K, an insulated metal spring so arranged that it can be pressed upon the anvil O by the disk P when this is pushed in to the box. Around the shaft of the crank is a spiral spring tending to retract the crank after it is pushed in.

The current enters by line 1, through binding-post F, to line 2, into the magneto by post L, through the magneto by J 3 N, into my apparatus through the coils of a magnet, as shown, to the frame-work of the machine, thence to the arm and contact-spring, as shown, then to the insulated metal-toothed sector shown out by M 5, into the bell by H, out by G, and to post E and line 7, as shown.

The method of operation is as follows: After the apparatus has been set as desired it will be necessary to call the attention of some one at the other end. If the crank were turned 20 and the magneto operated, the current therefrom would of course release the apparatus. To prevent this I arrange my circuits so that the apparatus can be cut out when the magneto or other calling key or device is operated.

Manifestly, the cutting out of the apparatus can be effected either by shunting it or by a direct severing of its circuit-connections at some point, and I desire to be understood as 30 including both of these arrangements under the term "cut-out." I prefer, however, to provide a shunt instead of severing the circuit, and it is this arrangement which I have shown in the drawings.

The shunting operation can be accomplished either manually, or, which is preferable, automatically. This automatic operation can be brought about in many ways, one convenient way applicable where a crank is used (as in 40 the present case) to send in a call is represented in the drawings. When the operator takes hold of the crank to turn it, he at the same time pushes its shaft in far enough to cause the contacts K O to come together. When 45 this takes place, the current upon leaving J will go to 3, and instead of going through the resistance of the magnets of my transmitter and bell will of course take the path of practically no resistance—switch K', 8, E, and 7.

Of course, instead of being shunted, as here shown, the automatic apparatus might be cut out entirely, and this I do upon certain occasions; but I prefer in general to shunt the apparatus as here shown, as by this means the 55 continuity of the circuit is never broken and the risk of a break in the circuit is thereby avoided. Of course it is not necessary that the bell should be separate from the magneto, as here shown, it being so shown merely for 60 the convenience of illustration. In many forms of magneto-bell the "ringer" is automatically cut out whenever the generator is being worked. In this form I insert my apparatus in the ringer-circuit, so as to be cut

out with it. In this case, of course, the taps 65 of the bell will correspond with the signal transmitted; but, when desirable, this can be avoided and the bell cut out, by means that I do not herein claim, but make the subject of a separate application filed November 20, 70 1884.

What I claim as of my own invention, and desire to secure by Letters Patent, is—

1. The combination, with a single circuit, a latent-signal transmitter, and calling apparatus for informing the receiving-station that the latent-signal transmitter is set, of a circuit-changer at the transmitting-station, whereby the call may be operated without thereby releasing the latent-signal transmitter, substantially as described.

2. The combination, with a single circuit, a latent-signal transmitter, and calling apparatus for informing the receiving-station that the latent-signal transmitter is set, of a circuit-changer connected with and operated by the calling apparatus, substantially in the manner hereinbefore described.

3. The combination, with a single circuit, a latent-signal transmitter, and calling apparatus for informing the receiving-station that the latent-signal transmitter is set, of a normally-open shunt which when closed offers to the current actuating the call-receiving apparatus a path of less resistance without breaking the continuity of the circuit, and a shunt-closing key whereby the call may be operated without thereby releasing the latent signal, substantially as described.

4. The combination, with a single circuit, a latent-signal transmitter, and calling apparatus for informing the receiving-station that the latent-signal transmitter is set, of a normally-open shunt which when closed offers to the current actuating the call-receiving apparatus a path of less resistance without breaking the continuity of the circuit, and a shunt-closing key whereby the call may be operated without thereby releasing the latent transmitter, the said key being connected with and operated by the calling apparatus, substantially as described.

5. The combination, in a circuit with normally no current in line, of a latent-signal transmitter, a magneto-generator, and a circuit-changer at the transmitting-station to be operated during the current generation by the magneto, whereby the current so generated will not release the latent transmitter, substantially as described.

6. The combination, in a circuit with normally no current in line, of a latent-signal transmitter, a magneto-generator, and a circuit-changer connected with and operated thereby during the act of current generation, whereby the current so generated will not release the latent transmitter, substantially as described.

7. The combination of a latent-signal transmitter, a magneto for calling attention of the receiving-office, a normally-open shunt, and a shunt-closing key, whereby the latent transmitter will not be released by the act of calling up the other station, substantially as described.

8. In combination with a latent-signal transmitter, a magneto for calling attention of the receiving-station provided with a shunt around the latent-signal transmitter and an

automatic shunt-closing key whereby the latent transmitter can remain set without being released during the operation of the magneto; substantially as described.

In testimony whereof I have hereunto set my hand this 10th day of February, 1885.

F. BENEDICT HERZOG.
